CLAIM

The ornamental design for a speaker with display, as shown and described.

DESCRIPTION

FIG. 1 is a front elevation view of a speaker with display showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top, front perspective view thereof; and,

FIG. 8 is a top, front, left perspective view thereof, shown in an alternate position.

The shade lines in the Figures show contour and not surface ornamentation.

1 Claim, 8 Drawing Sheets
